UNITED STATES PATENT OFFICE.

RICHARD D. GALLAGHER, OF CHICAGO, ILLINOIS.

GUARD-RAIL CLAMP.

Application filed March 3, 1922. Serial No. 540,747.

To all whom it may concern:

Be it known that I, RICHARD D. GALLAGHER, a citizen of the United States, residing at Chicago, in the county of Cook and State of Illinois, have invented certain new and useful Improvements in Guard-Rail Clamps, of which the following is a specification.

My invention relates to rail clamps, and particularly to clamps suitable for guard rails, which clamps require no cotter pins or keys, and which are adaptable for application to all standard T rails.

An object of the invention is to provide a guard rail clamp which is rigid and at the same time is adapted to permit adjustment of the rails in the clamp for purposes of alignment.

Another object of the invention is to provide an effective, strong and durable clamp for fastening a guard rail to a track rail without the use of spikes which clamp includes a yoke and means cooperating with the yoke whereby a yoke may be used with rails of different cross-sections, weights and dimensions thereby eliminating special yokes for rails of various sizes.

A further object of the invention is to provide a clamp for securing guard rails to track rails including a yoke adapted to underlie the rails and having upturned ends and wedge means cooperating with the ends of the yoke for gripping the rails the wedge ends having a plurality of parallel surfaces inclined to the horizontal.

A further object of the invention is to improve guard rail clamps for general, successful commercial use.

Generally speaking, I carry out the preferred embodiment of the invention by employing a yoke of cast metal having jaws which are sufficiently far apart to receive therebetween a track rail and a guard rail and the clamps of my invention.

The above recited and other objects of the invention will be apparent from the following description and drawings and will be particularly pointed out in the appended claims.

In the drawings:

Figure 1 is an elevational view of the preferred embodiment of the invention.

Figure 2 is an elevational view similar to Figure 1, showing certain of the elements comprising the clamp of my invention, and

Figure 3 is a perspective view of the rail brace employed.

The yoke 5 is substantially U shape in elevation and is made preferably of cast metal. The yoke has jaws 6 and 7 spaced sufficiently to permit the reception of track rail A and a guard rail B, together with the necessary means for fastening the rails in the yoke. This clamp is adapted to be applied to the rails between the ties and is in no manner fastened to the ties. The jaw 7 has an inclined surface which inclines outwardly from top to bottom; a lug 9, preferably square in cross section, projects from the surface 10. A block 11 is provided having a square opening therein for receiving the lug 9, which block is adapted to rest against the inclined surface 10, when the guard rail B is in position in the yoke. This block 11 forms a bearing for the guard rail as shown in Figure 1. Between the track and guard rails, spacers 12 and 13 are provided for purposes well understood.

The clamp of my invention consists in forming the jaw 6 with a downwardly inclined surface 16, similarly inclined surface 16^a parallel to the surface 16, but in a different plane and connecting these inclined surfaces with a substantially horizontal surface 16^b. These are shown in dotted line in Figure 2. A bolt 18 is secured in the jaw 6 in any suitable manner, either by casting the bolt when the yoke is made or by providing a slot 26, which is in width equal to the width of the head of bolt and receives the bolt to prevent turning of the same therein. In Figure 3 a rail brace is shown having inclined surface 21 and 22, an elongated centrally disposed opening 19 therein, and shoulders 23 and 24 which when in position against the track rail A bear against the under side of the head and the top of the base, respectively. A nut 20 may be applied after the brace is in position to force the brace against the rail. The manner of applying the rail clamp of my invention is as follows: Yoke 5 is applied from underneath the rails and the block 11 placed in position against the guard rail B. The separator blocks 12 and 13 are then applied and moved relatively to each other to secure the proper space between the track and guard rails A and B, whereupon the rail brace 17 is applied over the bolt 18 as shown in Figure 1 and the nut 20

applied to the bolt, which when turned down, will cause a wedging of the brace against the rail by reason of the inclined surface contact between the brace and the surfaces 16 and 16^a formed in the jaw 6 of the yoke. The brace is guided between flanges 6^a and 6^b so as to be held against lateral displacement under wedging action.

If alignment of the rail A is desired the bolt 10 may be unfastened and the separator members 12 and 13 adjusted to properly align rail A, whereupon tightening the nut 20 will clamp the rail firmly in position in the yoke.

15 It will be noted that the guard rail clamp of my invention eliminates cotter pins and keys and that the yoke is adaptable for all standard sections of T rails. The clamp is positive in operation, easily applied, adjusted and removed, and permits movement of the rails therein for purposes of alignment. The use of the inclined planes in the rail brace and yoke jaw insure quick and positive action of adjustment and locking 20 and securely fastens the several parts against displacement.

While I have described more or less precisely the details of construction of my invention, I do not wish to be understood as 30 limiting myself thereto as I contemplate changes in form and proportion of parts and the substitution of equivalents as circumstances may suggest or render expedient without departing from the spirit of my 35 invention.

I claim:

40 1. A guard rail clamp including a yoke adapted to underlie a track rail and a guard rail and having upwardly directed ends, one of said ends being formed with two parallel surfaces inclined to the horizontal, a wedge member having similar parallel and

inclined surfaces for cooperating with said ends, and means for moving said wedge on said yoke for clamping purposes.

45 2. A guard rail clamp including a substantially U shaped yoke adapted to receive a track rail and a guard rail, one of the ends of said yoke being adapted for engaging a rail, the other end of the yoke being formed 50 with two surfaces which are in parallel planes and inclined to the horizontal, a wedge having similarly inclined surfaces for cooperating with said end, adjustable separators adapted to be inserted between said rails, and means carried by said yoke for causing movement of said wedge on said yoke end for effecting clamping engagement of said clamp with said rails.

55 3. A guard rail clamp including a yoke adapted to underlie a track rail and a guard rail, said yoke arranged with its ends extending upwardly, a filler carried by one end of the yoke adapted to rest against one of said rails, the other end of said yoke having a plurality of parallel surfaces which are inclined to the horizontal, and a wedge member having similarly inclined surfaces for 60 cooperating with said yoke for engaging the other of said rails, and means associated with said yoke for actuating said wedge member for clamping purposes.

65 4. A guard rail clamp including a yoke having one end formed to provide two surfaces which are parallel and inclined to the 70 horizontal, a wedge member having similar surfaces and cooperating therewith, and means for moving said member on said surfaces for clamping rails against the other end of said yoke.

75 Signed at Chicago, Illinois, this 23rd day of February, 1922.

RICHARD D. GALLAGHER.
